UNITED STATES PATENT OFFICE.

CHARLES M. SIEBERT, JR., OF COLUMBUS, OHIO.

CUP OR HEAD FOR MASSAGE DEVICES.

No. 893,021.

Specification of Letters Patent.

Patented July 14, 1908.

Application filed October 18, 1907. Serial No. 397,970.

To all whom it may concern:

Be it known that I, CHARLES M. SIEBERT, Jr., citizen of the United States, residing at Columbus, in the county of Franklin and State of Ohio, have invented certain new and useful Improvements in Cups or Heads for Massage Devices, of which the following is a specification.

My invention relates to the improvement of cups or heads for massage devices, and has particular relation to cups of that class of massaging machines or devices in which an interrupted air current is used to produce the desired action on the skin.

The objects of my invention are to provide an improved cup or massaging head of this class with a flexible disk of yielding material which is adapted to have imparted thereto a rapid vibratory motion and which will readily expand and contract from the vibrations imparted thereto; to so construct my improved cup as to relieve the vibrating disk from undue expansion and to produce other improvements the details of which will be more fully pointed out hereinafter. These objects I accomplish in the manner illustrated in the accompanying drawing, in which—

Figure 1 is a view in elevation of a massaging machine handle, showing my improved cup connected therewith, Fig. 2 is a central vertical section of the cup on line $x-x$ of Fig. 3, and, Fig. 3 is an end view of the cup.

Similar numerals refer to similar parts throughout the several views.

In carrying out my invention, I employ a cup body 1 formed of hard rubber, fiber or other suitable material, said cup body comprising a straight tubular shank portion 1^a and an enlarged circular head portion 1^b, the latter having its periphery threaded, as shown in the drawing. The outer face or end of the enlarged portion 1^b is concaved to the cup shape shown at 2 in Fig. 2. The cup body 1 has formed therethrough a central bore or opening 3, the outer reduced end portion of which communicates, as shown, with the center of the recessed portion 2.

For the purpose hereinafter set forth, I provide a comparatively small air port 4 which extends from the recessed portion 2 cut through the body of the cup as indicated.

5 represents a vibrating disk which is preferably of thin sheet rubber, although as will be obvious, other well known flexible yielding material might be employed. This disk has

its border or portion adjoining its edges, clamped or held firmly against a gasket or ring 6 preferably of paper, which in turn is held against the outer end or rim of the enlarged head 1^b of the recess 2, by means of a clamping ring 7, the latter comprising a straight portion having internal threads and an inturned flange portion 7^a.

As shown in the drawing the threaded portion of the clamping ring is adapted to be screwed into engagement with the threads of the enlarged portion 1^b of the cup, while the inwardly flanged portion 7^a is adapted as shown to be thus clamped against the outer surface of the disk 5, thereby holding the edge portions of said disk closely in engagement with the head of the cup. It will be understood that the paper gasket 6 is employed for the purpose of preventing the rubber disk from slipping or wrinkling when the clamping ring is being screwed into place.

The cup or massaging head formed as above described is adapted to be connected in the usual manner with the neck extension 8^a of a tubular handle 8, which in turn is connected with an air conducting pipe 9.

In the operation of the class of massaging devices to which my invention particularly applies, an air pump and controlling mechanism is employed by means of which air is alternately injected through the tubular handle and into the cup and withdrawn therefrom, this operation being sufficiently rapid to result in a corresponding rapid inward and forward or vibratory motion of the flexible disk 5.

In utilizing my device the outer surface of the disk is placed against the surface to be massaged, with the result that the skin of the person being operated upon is subjected to the action of the vibratory movement of the disk. In order to prevent over-distension of the disk, I have provided the air outlet port 4 which will afford relief from undesirable air pressure.

What I claim is:

1. In a massage device, the combination with the tubular body having a cup-like recess in its outer end, and means for connection with an air conducting pipe, of a yielding disk of comparatively thin material clamped over the mouth of the cup recess.

2. In a massage device, the combination with the tubular body having a cup-like recess in its outer end, and means for connection with an air conducting pipe, of a yield-

ing disk of comparatively thin material detachably clamped over the mouth of the cup recess.

3. In a massaging device, the combination with the body having an opening therethrough and a cup-like recess in its outer end, and an air port leading from said recess through said cup body, of a flexible disk secured over the mouth of said recess, and

means for connecting said cup body with an air conducting pipe.

In testimony whereof I affix my signature in presence of two witnesses.

CHARLES M. SIEBERT, Jr.
